ELECTRIC SWITCH

George J. Meuer, Milwaukee, Wis., assignor to
 Cutler-Hammer, Inc., Milwaukee, Wis., a corporation of Delaware

Application May 28, 1937, Serial No. 145,318

14 Claims. (Cl. 200—6)

This invention relates to improvements in electric switches, and the invention relates more particularly to rotary switches of the slow-make, slow-break type.

5 A primary object of the invention is to simplify the construction and improve the operation of switches of the aforementioned character.

Another object is to provide a single form of molded insulating base which may be employed 10 in constructing switches having various different circuit controlling characteristics.

Another object is to minimize the number of 15 different parts required for construction of switches having such different electrical control characteristics.

Another and more specific object is to provide 20 a switch having a set or sets of contacts which are normally biased to open-circuit position, together with simple and efficient means for effecting control of such contacts.

Another object is to provide a switch having a contact actuating cam consisting of a flat punched plate of insulating material.

Another object is to provide an alternating current controlling switch of the aforementioned character which is particularly well adapted for use in conjunction with relatively small size radio rheostats and the like.

Various other objects and advantages of the 30 invention will hereinafter appear.

The accompanying drawings illustrate certain embodiments of the invention which will now be described, it being understood that the embodiments illustrated are susceptible of modification 35 in respect of certain structural details thereof without departing from the spirit and scope of my invention as defined in the appended claims.

In the drawings,

Figure 1 is a top plan view (double-scale) of a 40 double pole, slow-make, slow-break switch as constructed in accordance with my invention.

Fig. 2 is a perspective view, in separated relation, of the parts of the switch shown in Fig. 1.

Fig. 3 is a view, partly in elevation and partly in vertical section, illustrating the switch of Figs. 1 and 2 as combined with a radio rheostat or potentiometer.

Fig. 4 is a sectional view on the irregular line 4—4 of Fig. 1, the cam plate being shown in a 50 rotary position to provide for interruption of the controlled circuit.

Fig. 5 is a view similar to Fig. 1,—but illustrating a modified arrangement of contacts adapted 55 to provide a switch of the so-called three-way type.

Fig. 6 is a sectional view on the irregular line 6—6 of Fig. 5.

Fig. 7 is a bottom plan view of a switch generally similar to that shown in Fig. 1,—but involving use of a bus member so connected as to provide 5 a switch of the so-called three-wire type.

Fig. 8 is an elevational view of a device having a pair of switches mounted in tandem relation to a radio rheostat or the like,—certain parts being broken away to illustrate the rotatable operating 10 means common to the rheostat and the switches.

Fig. 9 is a top plan view (actual size) of a modified form of double pole slow-make, slow-break switch as constructed in accordance with my invention.

Fig. 10 is an enlarged view similar to Fig. 9, but with a portion of the metal casing cut away and with the insulating actuating plate omitted for purposes of illustration.

Fig. 11 is a fragmentary view, partly in elevation and partly in vertical section, illustrating the manner of attaching the switch of Figs. 9 and 10 to the metal casing or housing of a radio rheostat or the like.

Fig. 12 is a bottom plan view of the switch 25 shown in Figs. 9 to 11.

Fig. 13 is an enlarged top plan view of a modified form of slow-make, slow-break switch of the single pole type.

Fig. 14 is a view similar to Fig. 13, but with a 30 portion of the metal casing cut away and with the insulating actuating plate omitted for purposes of illustration.

Fig. 15 is a view, partly in elevation and partly in vertical section, of the switch shown in Figs. 35 13 and 14,—the switch contacts being shown in open-circuit position, and

Fig. 16 is a bottom plan view, actual size, of the switch shown in Figs. 13 to 15.

Referring first to Figs. 1 to 4, inclusive, the 40 numeral 25 designates a molded insulating base of substantially cylindrical form,—said base having a substantially cylindrical recess 26 formed therein and opening to the upper surface thereof. Positioned centrally of recess 26 and formed integrally with the bottom wall thereof is an annular raised portion 27 having a flat upper surface 28 located a predetermined distance below the upper surface of base 25, as best illustrated in Fig. 3. Extending radially from raised portion 27 45 is a rib 29 having a flat upper surface 30 located in the plane of surface 28. Also extending radially from raised portion 27 is a rib 31 arranged in diametrical alinement with rib 29. The upper surface 32 of rib 31 is preferably located in a 50 55

plane below the plane of surfaces 28 and 30, to accommodate a contact member employed to provide a switch of the three-way type, as herein-after described in connection with Figs. 5 and 6.

5 The raised portion 27 surrounds a recess 33 which provides rotary clearance for the downwardly extending arms of an inverted U-shaped metal actuating member 34 (Fig. 3) which is rigidly attached to the lower end of a rheostat 10 operating shaft 35, as by upsetting the reduced lower end portion 36 of the latter over the connecting portion of member 34. Adapted to seat upon the bottom wall of recess 26 (Figs. 1 and 4) on opposite sides of rib 31, and in closely adjacent relationship to the latter, is a pair of one piece combined contact and wiring terminal members 37 of identical form,—said members having openings 38 to accommodate the upwardly extending hollow shanks of rivets 39 15 which are upset over said members to rigidly secure the same to the bottom wall of recess 26. Members 37 are preferably provided with arcuate wings 40 which are offset upwardly from the bottom wall of recess 26 to provide the pair of stationary contacts for the switch. Members 37 are provided with wiring terminal portions 41 extending radially from the contact portions 40 and then downwardly at substantially right angles thereto.

20 Base 25 is provided with auxiliary recesses 42 and 43 and with rectangular openings 44 and 45 to accommodate said terminal portions 41, whereby the latter are exposed below the lower surface of base 25,—said terminal portions having the usual openings to facilitate attachment of circuit wires. Secured to the bottom wall of recess 26 in substantially diametrically opposed relationship to members 37 are the flat portions 46 and 47 of a second pair of one-piece combined 25 contact and wiring terminal members,—said flat portions having openings to accommodate the hollow shanks of a pair of rivets 48, which are upset thereover as shown in Fig. 1.

25 Bent upwardly at an angle to the respective flat portions 46 and 47 are oppositely curved arcuate resilient arms 49 and 50, the free ends 51 and 52 of which respectively overlie the aforementioned contact portions 40 and the pair of members 37. Arms 49 and 50 are sheared or slit 30 at corresponding points 53 and 54 in the length thereof, but at different points with respect to the arcuate center lines thereof respectively. The relatively narrower portion at the outside of slit 53 is bent or deformed to provide an upwardly converging double-inclined cam portion 55; and the relatively narrower portion at the inside of slit 54 is bent or deformed to provide an upwardly converging double-inclined cam portion 56. Base 25 is provided with an auxiliary 35 recess 57 to accommodate a lateral extension 58 of flat portion 46,—and projecting downwardly at a right angle to extension 58 is a wiring terminal portion 59; base 25 being provided with a substantially rectangular opening 60 to accommodate wiring terminal portion 59, whereby the perforated lower end portion of the latter is exposed below the lower surface of base 25. Base 25 is also preferably provided with a recess 61 40 to accommodate a lug 62 extending laterally from flat portion 46 to assist in preventing movement of the latter relatively to the base.

Base 25 is similarly provided with an auxiliary recess 63 to accommodate a lateral extension 64 of flat portion 47,—and projecting downwardly at a right angle to extension 64 is a wiring ter-

5 minal portion 65; base 25 being provided with a substantially rectangular opening 66 to accommodate wiring terminal portion 65, whereby the perforated lower end portion of the latter is exposed below the lower surface of base 25. Base 25 is also preferably provided with a recess 67 to accommodate a lug 68 extending laterally from flat portion 47 to assist in preventing movement of the latter relatively to the base.

10 As will be apparent from the foregoing description and the drawings, the combined contact and terminal members, including the respective portions 46 and 47, are merely bent in opposite directions from identical blanks, after shearing thereof to provide the respective slits 53 and 54, 15 to provide right-hand and left-hand members. By this arrangement only two forms of metal blanks are required for constructing a double pole switch, thus reducing the cost thereof.

15 Positioned within recess 26 and adapted to seat upon the flat surfaces 28 and 30 in a relation substantially flush with the upper surface of base 25 is a flat punched insulating plate 69 of substantially circular contour. Plate 69 is provided with a centrally located rectangular opening 70, which is adapted to accommodate with a fairly close fit the downwardly extending arms of actuating member 34 (Fig. 3),—it being understood that for this purpose opening 70 is of slightly greater length than breadth. Plate 30 20 69 is provided with an opening or peripheral notch 71 preferably positioned radially of opening 70, and with the walls of said notch arranged in parallel relation to the walls of opening 70. Notch 71 is adapted in one rotary position of 35 plate 69 to accommodate the double-inclined cam portion 55, whereby arm 49 by its own resiliency is adapted to raise the free end portion 51 thereof out of engagement with the stationary contact portion 40 associated therewith, as best illus- 40 trated in Fig. 4.

25 Angularly spaced in a clockwise direction from notch 71 in plate 69 (with reference to Fig. 2) is a rectangular opening 72 which is adapted to accommodate the double-inclined cam portion 45 56 in the aforementioned rotary position of plate 69, whereby arm 50 by its own resiliency is adapted to raise the free end portion 52 thereof out of engagement with the stationary contact portion 40 associated therewith (see Fig. 4). The 50 arrangement is such that cam 55 will not enter opening 72 and cam 56 will not enter notch 71 in any rotary position of plate 69.

30 Thus with the switch parts in the open-circuit position thereof shown in Fig. 4 it will be apparent 55 that upon initial clockwise rotation of plate 69 (the latter being restrained against upward displacement by the means hereinafter described) one end wall of notch 71 will coact with cam 55 and one end wall of opening 72 will coact with cam 56 to effect movement of the free ends 51 and 52 into engagement with the stationary contacts respectively associated therewith; and engagement of the movable and stationary contact elements will be maintained during further clockwise movement of plate 69, throughout the range of movement provided for shaft 35. As set forth in my application Serial No. 144,891, filed May 26, 1937, for electric switches of the slow-make, slow-break type, it is customary to provide means of 60 known form for limiting the rotary movement of the rheostat shaft to less than 360 degrees.

35 However, it will be apparent to those skilled in the art, and I desire to have it understood, that the switch mechanism herein disclosed is adapted 75

for operation to interrupt the controlled circuit during a relatively small portion of one complete rotation of cam plate 69 and to complete such circuit during the remainder of such complete rotation,—regardless of the direction of rotation of said plate. Moreover, it will be apparent that if desired the length of notch 71 and of opening 72 might be substantially increased, to provide for interruption of the controlled circuit in other rotary positions of plate 69, or during a greater portion of the rotary movement of the latter. It will be understood that in any event the longitudinal walls of notch 71 and opening 72 may be in the form of arcs parallel to the periphery of plate 69.

Base 25 is preferably provided with a recess 13 concentric with and of smaller diameter than recess 33,—the bottom surface of the base being provided with a countersink or recess 74 (Fig. 3) 20 concentric and commensurate with recess 13, whereby a relatively thin diaphragm 75 is provided. Said diaphragm may be readily removed by broaching to provide rotary clearance for an extension of the switch actuating member,—as 25 shown, for instance, in Fig. 8. Where a single switch is associated with a rheostat 76, as shown in Fig. 3, the diaphragm 75 is permitted to remain intact. In Fig. 3 the rheostat 76 is shown as provided with a stamped sheet metal shell 77 30 having arms 78 and 79 of arcuate form in cross section which fit into suitable grooves in the base of rheostat 77 and in grooves 80 and 81 in the periphery of base 25.

Interposed between rheostat base 76 and switch base 25 is an annular sheet metal member 82, the same having upwardly bent lugs 83 and 84 to engage, and said lugs having openings to accommodate, the aforementioned arms 78 and 79. Arranged on opposite sides of member 82 are annular insulating members 85 and 86,—the latter overlying a portion of plate 69 to restrain the same against upward displacement. Arm 80 is provided with a pair of lugs 87 and 88 (Fig. 7) and arm 81 is provided with a lug 89,—said lugs being bent inwardly into corresponding recesses provided in the bottom surface of base 25, as indicated in Figs. 3 and 7, to retain the rheostat and switch in assembled relation.

As shown in Fig. 3, an externally threaded hollow metal bushing 90 is attached to shell 77 to provide for one-hole mounting of the complete device to a panel or the like, as by means of a clamping nut (not shown),—shell 77 being preferably provided with upstanding lugs 91 and 92 formed integrally therewith to assist in maintaining parallelism between said shell and the panel to which it is attached.

The aforescribed arrangement of the switch parts and the operating means therefor is such that a slow-make and a slow-break of the controlled circuit is provided upon operation of the rheostat in the usual manner. The aforescribed switch has a rating or current controlling capacity of 3 amperes at 125 volts A. C.; 1 ampere at 250 volts A. C.; or an alternative rating of 15 amperes at 12 volts D. C.

In the three-way switch illustrated in Figs. 5 and 6 certain of the identical parts aforescribed are employed, and such parts have been given 70 corresponding numerals of reference. However, the pair of contacts shown at the left-hand side of the insulating base in Fig. 1 have been omitted from the base of Fig. 5. Within recess 26 at the lower left-hand side thereof (Fig. 5) I position a different form of combined contact and wiring

terminal member,—the latter having a flat portion 93 which is secured by a rivet 39. Extending upwardly at a right angle to flat portion 93 is a portion 94, and extending from the latter in a plane adapted to clear the upper surface 32 of rib 31 (see Fig. 6) is a flat contact portion 95 which overlies the aforescribed contact portion 51. Extending downwardly at a right angle to flat portion 93 is a wiring terminal portion 96, which is perforated as shown to facilitate attachment of a circuit wire. Located in the plane of flat portion 93 is a lug 97 which assists in preventing rotary displacement of this combined contact and terminal member with respect to base 25.

An insulating cam plate 69 identical with that aforescribed may be employed in the switch of Figs. 5 and 6, it being understood that only the notch 71 of plate 69 is adapted to function. As shown in Fig. 6, the arrangement is such that in a given rotary position of plate 69, wherein the notch 71 accommodates the double-inclined cam 55, the contact portion 51 is moved upwardly, by the resiliency of arm 49, into engagement with the contact portion 95, whereby a circuit connection is provided between the lower left-hand terminal member of Fig. 5 and the upper right-hand terminal member of this figure. Upon clockwise rotation of plate 69, the end wall of notch 71 cooperates with one side of cam 55 to depress the latter to effect engagement of contact portion 51 with stationary contact portion 40, whereby a circuit connection is provided between the two terminal members at the right-hand side of the base in Fig. 5. Such last mentioned circuit connection will of course be maintained throughout the remainder of the clockwise movement of plate 69 by the rheostat shaft, as aforescribed, and pending counterclockwise movement of plate 69 to the rotary position thereof illustrated in Fig. 6.

It is to be understood that a plate like 69 (Fig. 2) but omitting the opening 72 therefrom might be employed for the three-way switch of Figs. 5 and 6. For purposes of economy in manufacture, however, I prefer to employ the particular form of plate 69 shown in Fig. 2 for each of the various forms of switches illustrated in Figs. 1 to 8, inclusive. In this connection, it may be noted that a single pole on and off switch may be provided by merely omitting the contact and terminal members 95, 96 from the switch of Figs. 5 and 6. Similarly, a single pole switch may be provided by omitting the pair of contact and terminal members from either the left-hand side or the right-hand side of Fig. 1. With reference to Figs. 1, 2, 5 and 7 it will be noted that I provide base 25 with a pair of diametrically opposed openings 98 and 99 which are adapted to accommodate the shanks of headed rivets or bolts (not shown) affording an alternative means for attaching the switch base 25 to a suitable support.

In Fig. 7, I have illustrated a so-called three-wire switch which is structurally like the double pole switch of Figs. 1 to 4, inclusive,—with the exception that a bus member or conductive strip 100 is secured in position by the rivets 48, whereby the terminal portions of the two movable contact elements of the switch are continuously electrically connected with each other. Inasmuch as only one wiring terminal portion is required for the pair of movable contacts in Fig. 7, I also prefer to shear or cut off that part of one terminal portion which would project below the lower surface of base 25,—as indicated at 65a in Fig. 7. In Fig. 7 I have shown the three wiring terminal

portions 59, 41, 41 bent radially outward within suitable grooves provided in the lower surface of base 25, and in a relationship substantially flush with the latter.

5 In Fig. 8 I have shown a rheostat 76 having a pair of switch bases 25, 25 mounted in tandem relationship thereto, said parts being retained in assembled relation as by means of a metal shell 77^a, having a pair of arms, one of which is shown at 78^a, of the required length, and having lugs, such as the lugs 81, 88 and 89 aforescribed, formed integrally with the lower ends thereof. The switch mechanisms carried by the two bases 25 in Fig. 8 may have any desired circuit controlling characteristics,—but for present purposes it may be assumed that the switch 25 adjacent to the rheostat 76 is of the double pole type illustrated in Figs. 1 to 4; whereas the lower switch 25 may be assumed to be of the three-wire type illustrated in Fig. 7. The cam plate 69 of the upper switch in Fig. 8 is adapted to be driven by the U-shaped metal member 34 aforescribed,—whereas the cam member 69 of the lower switch is adapted to be driven by a member 101 of rectangular form in cross section which telescopes into the U-shaped member 34. I have shown a relatively thin insulating plate 102 interposed between the switch bases 25,—but this insulating plate may be omitted if desired. Shell 77^a is also preferably provided with the diametrically opposed upstanding spacing lugs, one of which is shown at 91^a,—and an externally threaded hollow metal bushing 90 is non-rotatably attached to said shell.

35 In Figs. 9 to 12, inclusive, I have illustrated a modified form of double pole switch, which is of substantially smaller size than that shown in Figs. 1 to 4, inclusive,—as indicated by the actual-size showing in Fig. 9. This modified form of switch comprises a substantially cylindrical insulating base 103 having a substantially cylindrical recess 104 formed therein and opening to the upper surface thereof. Formed integrally with the bottom and side walls of recess 104 and extending diametrically across the same, in a plane offset downwardly from the upper surface of base 103, is a rib 105, which is preferably provided with a centrally arranged enlargement 106.

Arranged within recess 104 on the right-hand side of rib 105 is a pair of one-piece combined contact and wiring terminal members 107 and 108, and arranged in said recess on the left-hand side of rib 105 is a second pair of one-piece combined contact and wiring terminal members 109 and 110. Members 107 and 109 are formed right- and left-hand from blanks of identical form; and members 108 and 110 are likewise formed right- and left-hand from blanks of identical form. Four rivets 111 of identical form are employed to secure the four combined contact and terminal members to base 103. The wiring terminal portions 107^a, 108^a, 109^a and 110^a of said members penetrate correspondingly shaped openings in base 103 and are exposed below the lower surface of the latter to facilitate attachment of circuit wires.

70 The contact portions of members 107 and 109 comprise resilient arms 107^b, 109^b, the tips 107^c and 109^c of which respectively overlie and are biased out of engagement with the stationary contact portions of members 108 and 110. The outer portion of arm 107^b is bent upwardly to provide a double-inclined cam 107^d; and the inner portion of arm 109^b is bent upwardly to provide a double-inclined cam 109^d. Rotatably posi-

tioned within recess 104 is a flat punched cam plate 112 of circular form; said plate having a notch 113 to accommodate cam 107^d in one rotary position of said plate, and an opening 114 to accommodate cam 109^d in said one rotary position of the plate, as shown in Fig. 9, whereby the contact tips 107^c and 109^c are disengaged from the stationary contacts 108 and 110.

Base 103, with the switch parts assembled with respect thereto is inserted upwardly into a cylindrical metal shell 115 having an inwardly extending flange 116 which partly overlies the cam plate 112 to prevent substantial upward displacement of the latter. Flange 116 is preferably cut away at two diametrically opposed points, as shown at 117 and 118 in Fig. 9, to insure proper electrical clearance between the same and cam 107^d upon assembly of base 103 in one or the other of two diametrically opposite rotary relationships.

As indicated in Fig. 12 (and as illustrated in the similar arrangement of Fig. 15), the shell 115 is of slightly less depth than base 103, to provide for lateral bending of the terminal portions 107^a, 108^a, 109^a and 110^a without danger of electrical contact between the same and said shell. Base 103 is provided in its lower surface with a pair of diametrically opposed recesses 119 and 120 into which the lugs 121 and 122 may be bent, in one or the other of two diametrically opposite rotary positions of said base and shell, whereby all of the parts are retained in assembled relation.

Shell 115 is also provided at its upper end with a pair of diametrically opposed upstanding lugs 123 and 124, said lugs being adapted to be accommodated within an opening 125 (Fig. 11) in the bottom wall 126 of a sheet metal shell 127 adapted to house a rheostat of suitable form,—the switch shell 115 and the rheostat shell 127 being preferably of substantially the same diameter. Said lugs 123 and 124 are bent outwardly over the bottom wall 126 of the rheostat shell to retain the latter and the switch shell against rotary and longitudinal displacement relatively to each other. Cam plate 112 is provided (Figs. 9 and 11) with an opening 128 to receive an extension 129 of the operating shaft of the rheostat to provide for positive driving of the former by the latter.

The single pole switch illustrated in Figs. 13 to 16 is in general quite similar to the double pole switch of Figs. 9 to 12. Fig. 16 shows the actual size of this single pole switch. In Figs. 13 to 16 the numeral 130 designates a molded insulating base of substantially cylindrical form, said base having a substantially cylindrical recess 131 formed therein and opening to the upper surface thereof. Secured to the bottom wall of recess, as by means of a pair of rivets 132 is a pair of one-piece combined contact and wiring terminal members 133 and 134, member 133 having a relatively long resilient arm 133^a of arcuate form the tip 133^b of which overlies and is biased away from the relatively short arcuate arm 134^a of member 134 which forms the stationary contact of the switch.

Member 133 is provided with a perforated wiring terminal portion 133^c, and member 134 is provided with a perforated wiring terminal portion 134^b,—said wiring terminal portions being exposed below the lower surface of base 130, as shown in Figs. 15 and 16, and the same being bendable outwardly over said lower surface, to reduce the over-all depth of the switch. Arm

133^a is provided intermediate the length thereof with an upward deformation to provide a double-inclined cam 133^d. The portion of the area of recess 131 not occupied by members 133 and 134 5 is in the form of a ledge 135 of irregular contour, said ledge providing a flat bearing surface for a cam plate 136, whereby the latter is positioned substantially flush with the upper surface of base 130. Plate 136 is provided with a 10 peripheral notch 136^a which is adapted in one rotary position thereof to accommodate cam 133^d (Figs. 13 and 15) to permit disengagement of contact portion 133^b from stationary contact portion 134^a,—said plate 136 acting in all other 15 rotary positions thereof to effect engagement of contact portion 133^b with contact portion 134^a.

Plate 136 is provided with an opening 136^b to receive the extension of a rheostat shaft or the like, whereby said plate is positively driven. 20 Because of the symmetrical arrangement of notch 136^a with respect to opening 136^b, it will be understood that plate 136 may be assembled with either face thereof turned toward recess 131. Base 130 with the parts thereof in position is 25 inserted upwardly into a cylindrical shell 137, the latter being provided at its upper end with an inwardly extending flange 137^a which overlies an annular portion of plate 136 to prevent substantial upward displacement of the latter.

As shown in Fig. 15, the shell 137 is of slightly 30 less depth than base 130, to insure electrical clearance between said shell and the terminal portions 133^c and 134^b upon outward bending of the latter.

35 Base 130 is provided in its lower surface with a pair of recesses 130^a, 130^b to respectively receive either of the inwardly bendable lugs 137^b formed integrally with the lower end of shell 137. Shell 137 is also provided at its upper end with 40 a pair of integral upstanding lugs 137^d and 137^e, which are adapted for attachment of shell 137 to a rheostat shell (not shown) in a manner similar to that shown in Fig. 11.

45 What I claim as new and desire to secure by Letters Patent is:

1. In an electric switch, in combination, a 50 molded insulating base having a recess formed therein and opening to the upper surface thereof, said base having a ledge formed integrally therewith and said ledge having a flat face offset upwardly from the bottom wall of said recess, a relatively thin flat insulating plate of substantially circular contour positioned within said recess and adapted to seat against said flat face in a relation substantially flush with the upper surface of said base, means for restraining said plate against substantial upward displacement, a 55 pair of contacts rigidly secured to the bottom wall of said recess, one of said contacts comprising a resilient arm the free end of which overlies and is biased out of engagement with the other contact, said arm having a cam-shaped boss formed upon the upper surface thereof, said plate having an opening formed therein to accommodate said boss in one rotary position of the former, said plate when rotated from said position cooperating with said boss to effect depression of said arm, whereby the free end of the latter is engaged with said other contact, and 60 means for effecting rotation of said plate in opposite directions respectively.

2. In an electric switch, in combination, a 65 molded insulating base having a recess formed therein and opening to the upper surface thereof, said base having a ledge formed integrally

therewith and said ledge having a flat face offset upwardly from the bottom wall of said recess, a relatively thin flat insulating plate of substantially circular contour positioned within said recess and adapted to seat against said flat face in a relation substantially flush with the upper surface of said base, means comprising a metal supporting member for said base, said supporting member having a flange for restraining said plate against substantial upward displacement, 10 a pair of contacts rigidly secured to the bottom wall of said recess, one of said contacts comprising a resilient arm the free end of which overlies and is biased out of engagement with the other contact, said arm having a cam-shaped 15 boss formed integrally therewith upon the upper surface thereof, said plate having an opening formed therein to accommodate said boss in one rotary position of the former, said plate when rotated from said position cooperating with said 20 boss to effect depression of said arm, whereby the free end of the latter is engaged with said other contact, means for effecting rotation of said plate in opposite directions respectively from and to said one rotary position thereof, said last mentioned means comprising a shaft having a positive driving connection with said plate, and means for limiting rotation of said shaft to an angle of less than 360 degrees.

3. A relatively small slow-make, slow-break 30 switch of the rotary type, said switch comprising a molded insulating base having a recess formed therein and opening to the upper surface thereof, said base having a ledge formed integrally therewith and said ledge having a flat face offset 35 upwardly from the bottom wall of said recess, a relatively thin flat plate of insulating material loosely fitting into said recess and adapted to seat against said flat face in a relation substantially flush with the upper surface of said base, 40 a metal shell surrounding said base and having a substantially annular flange overlying a portion of said insulating plate to retain the latter in assembled relation to said base, said shell having means engaging the lower surface of said base 45 to retain all of said parts in assembled relation, a pair of one-piece combined contact and wiring 50 terminal members rigidly secured to the bottom wall of said recess at one side of said ledge, each of said members having the wiring terminal portion thereof penetrating said bottom wall and exposed at the lower surface of said base, the contact portion of one of said members comprising a resilient arm the tip of which overlies the contact portion of the other member, said arm 55 having a cam portion formed integrally therewith and normally projecting above the plane of said flat face of the ledge, said insulating plate being provided with an opening to accommodate said cam portion in one rotary position of said 60 plate, whereby said contact portions are separated from each other to interrupt the controlled circuit, said insulating plate being adapted when moved from said one position to cooperate with said cam portion and depress said resilient arm, 65 whereby said contact portions are engaged with each other, and manually operable rotatable means having a positive driving engagement with said insulating plate.

4. A switch comprising a molded insulating 70 base having a substantially cylindrical recess formed therein and opening to the upper surface thereof, said base having a ledge formed integrally therewith and said ledge having a flat face offset upwardly from the bottom wall of 75

said recess, a relatively thin flat plate of insulating material loosely fitting into said recess and adapted to seat against said flat face in a relation substantially flush with the upper surface of said base, a metal shell surrounding said base and having a substantially annular flange overlying a portion of said insulating plate to retain the latter in assembled relation to said base, said shell having means engaging the lower surface of said base to retain all of said parts in assembled relation, a pair of combined contact and wiring terminal members secured to the bottom wall of said recess at one side of said ledge, each of said members having the wiring 10 terminal portion thereof penetrating said bottom wall and exposed at the lower surface of said base, the contact portion of one of said members comprising a resilient arm the tip of which overlies the contact portion of the other member, 15 said arm having a double-inclined cam portion formed integrally therewith and normally projecting above the plane of said flat face of the ledge, said insulating plate being provided with an opening to accommodate said cam portion 20 one rotary position of said plate, whereby said contact portions are separated from each other to interrupt the controlled circuit, said insulating plate being adapted when moved from said one position to cooperate with said cam portion 25 and depress said resilient arm, whereby said contact portions are engaged with each other to complete the controlled circuit, and manually rotatable means having a positive driving engagement with said insulating plate, said last 30 mentioned means including means for limiting the degree of rotation of said insulating plate.

5. A relatively small slow-make, slow-break switch of the rotary type for control of an alternating current circuit, said switch comprising a 40 molded insulating base having a substantially cylindrical main recess formed therein and opening to the upper surface thereof, said base having a ledge formed integrally with the bottom wall of said recess and extending diametrically across 45 the latter to divide the same into a pair of relatively shallow recesses of segmental form, a pair of one-piece combined contact and wiring terminal members rigidly secured to the bottom wall of each segmental recess at opposite ends 50 respectively of the latter, said members having the terminal portions thereof extending downwardly through the respective bottom walls and exposed upon the lower surface of said base, one contact portion of each pair comprising a resilient arm the tip of which overlies and is bent 55 toward the other contact portion of the pair, said arms being bent upwardly relatively to the bottom walls of the respective segmental recesses whereby said contact portions are normally 60 biased out of engagement with each other, each of said arms having a double-inclined cam portion formed integrally therewith and normally projecting above the plane of the upper surface of said ledge, a flat substantially circular insulating plate adapted to seat against the upper 65 surface of said ledge and being thereby positioned within said main recess in a relation substantially flush with the upper surface of said base, the lower surface of said plate being engageable with 70 said cam portions to depress said arms whereby the respective pairs of contact portions are engaged with each other in certain rotary positions of said plate, the lower surface of said plate being interrupted at points spaced angularly and radially from each other to accommodate said

cam portions in another rotary position of said plate whereby said pairs of contact portions are disengaged from each other under the bias of said resilient arms, means for retaining said plate in rotatably assembled relationship to said base, 5 and manually operable means for effecting rotation of said plate.

6. A switch comprising a molded insulating base having a recess formed therein and opening to the upper surface thereof, said base having 10 a ledge formed integrally with the bottom wall of said recess and extending diametrically across the latter to divide the same into a pair of relatively shallow recesses of segmental form, a pair of combined contact and wiring terminal members secured to the bottom wall of each segmental recess at opposite ends respectively of the latter, said members having the terminal portions thereof extending downwardly through the respective bottom walls and exposed upon the 20 lower surface of said base, one contact portion of each pair comprising a resilient arm the tip of which overlies and is bent toward the other contact portion of the pair, said arms being bent upwardly relatively to the bottom walls of the 25 respective segmental recesses whereby said contact portions are normally biased out of engagement with each other, each of said arms having a double-inclined cam portion formed integrally therewith and normally projecting above the 30 plane of the upper surface of said ledge, a flat insulating plate adapted to seat against the upper surface of said ledge and being thereby positioned within said main recess in a relation substantially flush with the upper surface of said base, 35 the lower surface of said plate being engageable with said cam portions to depress said cams whereby the respective pairs of contact portions are engaged with each other in certain rotary 40 positions of said plate; the lower surface of said plate being interrupted at points spaced angularly from each other to accommodate said cam portions in another rotary position of said plate whereby said pairs of contact portions are disengaged from each other under the bias of said 45 resilient arms, means comprising a metal supporting member for said base, said supporting member having a flange for retaining said plate in rotatably assembled relationship to said base, and means including a manually operable shaft 50 having a positive driving connection with said plate for effecting rotation of the latter, said last mentioned means including means for limiting rotary movement of said plate to an angle of less than three hundred and sixty degrees. 55

7. As an article of manufacture, a one-piece combined contact and wiring terminal member for electric switches of the slow-make, slow-break type, said member consisting of a punched and stamped sheet metal piece, said piece having a perforated intermediate portion to be rigidly secured flatwise to a suitable insulating support, a perforated wiring terminal portion bent downwardly at substantially a right angle to said intermediate portion for exposure of the former at 60 the lower surface of the support, and a resilient arm of arcuate contour extending laterally and upwardly from said intermediate portion at a predetermined angle thereto, said arm having a slit formed therein intermediate the ends thereof, and a portion of said arm at one side of said slit being bent upwardly to provide a double-inclined cam surface for cooperation with an actuating cam member of suitable form. 70

8. As an article of manufacture, a punched

sheet metal blank adapted for formation thereof into a right-hand or a left-hand combined contact and wiring terminal member for a rotary electric switch of the slow-make, slow-break type, said blank comprising an arcuate portion one end of which is provided with an opening to accommodate a securing element of suitable form, a perforated lateral extension at said end which is bendable in one direction or the other 10 at substantially a right angle thereto to provide a wiring terminal, said arcuate portion being bendable adjacent to said end thereof in a direction opposite to the direction of bending of said terminal portion, whereby an upwardly angled contact arm is provided upon securement of the member to a suitable support, said arm having a longitudinally extending slit formed intermediate the ends thereof, and the material on one side or the other of the slit being bendable upwardly to provide a double-inclined cam.

9. As an article of manufacture, a punched sheet metal blank adapted for formation thereof into a right-hand or a left-hand combined contact and wiring terminal member for a rotary electric switch of the slow-make, slow-break type, said blank comprising an arcuate portion one end of which is provided with an opening to accommodate a securing element of suitable form, a perforated lateral extension at said end which is bendable in one direction or the other 15 at substantially a right angle thereto to provide a wiring terminal, said arcuate portion being bendable adjacent to said end thereof in a direction opposite to the direction of bending of said terminal portion, whereby an upwardly angled contact arm is provided upon securement of the member to a suitable support, said arm having a longitudinally extending slit formed intermediate the ends thereof, and the material on one side or the other of the slit being bendable upwardly to provide a double-inclined cam, and said blank having an integral positioning lug located in the plane of the first mentioned end thereof for cooperation with shoulders formed on the aforementioned support.

10. As an article of manufacture, a punched sheet metal blank adapted for formation thereof into a right-hand or a left-hand combined contact and wiring terminal member for a rotary electric switch of the slow-make, slow-break type, said blank comprising an arcuate portion one end of which is provided with an opening to accommodate a securing element of suitable form, a perforated lateral extension at said end which is bendable in one direction or the other 20 at substantially a right angle thereto to provide a wiring terminal, said arcuate portion being bendable adjacent to said end thereof in a direction opposite to the direction of bending of said terminal portion, whereby an upwardly angled contact arm is provided upon securement of the member to a suitable support, said arm having a longitudinally extending slit formed intermediate the ends thereof, and the material on one side or the other of the slit being bendable upwardly to provide a double-inclined cam, and said blank having an integral positioning lug located in the plane of the first mentioned end thereof for cooperation with shoulders formed on the aforementioned support.

11. In a switch of the character described, in combination, a molded insulating base having a substantially cylindrical recess formed therein and opening to the upper surface thereof, a pair 25 of combined contact and wiring terminal mem-

bers rigidly secured to the bottom wall of said recess, one of said members having a resilient arm the contact portion of which overlies and is biased out of engagement with the contact portion of the other member, a third combined contact and wiring terminal member into engagement with the contact portion of which the contact portion of said resilient arm is adapted to move under said bias, said resilient arm having a double-inclined cam upon the upper surface thereof, a relatively thin flat plate of insulating material positioned and retained within said recess in a relation substantially flush with the upper surface of the latter, said plate having a central angular opening to provide a positive driving connection between the same and a rotatable operating member of suitable form, said plate having an eccentric opening formed therein to accommodate said cam in a given rotary position of said plate to provide for movement 30 of said arm to one extreme position thereof under its bias, and said plate cooperating with said cam to effect movement of said resilient arm to and retention thereof in its other extreme position against its bias upon rotary movement of said plate from the position thereof aforementioned.

12. In combination, a rotatable shaft having an inverted U-shaped sheet metal extension member rigidly attached to the end thereof for rotation therewith, a switch mechanism comprising a rotatable cam member having a rectangular opening formed therein to accommodate said extension for rotation thereby, a molded insulating base having a recess within which said cam member is rotatably seated, a second switch of the aforementioned character the insulating base of which is adapted to seat in tandem relation against said first mentioned base, a member of rectangular cross section telescoped into the open end of said U-shaped member and having a positive driving connection with the cam member of said second switch, said switch bases having substantially identical peripheral dimensions, a stamped sheet metal housing member having opposed arms insertable downwardly over said switch bases and interlocked with each of the same to prevent relative rotation thereof, said opposed arms having integral lugs bendable inwardly over the lower surface of said second switch base to retain all of said parts in assembled relation, each of said switches having at least one pair of contacts resiliently biased out of engagement with each other, and the cam members of said switches cooperating with said pairs of contacts to effect engagement and permit disengagement thereof in different rotary positions respectively of said shaft.

13. In an electric switch of the rotary type, in combination, an insulating base, a pair of combined contact and terminal members rigidly secured to said base, the contact portions of said members being positioned upon one surface of said base and the terminal portions of said members penetrating said base and being exposed at the opposite surface of the latter, the contact portion of one of said members comprising a resilient arm the free end of which overlies and is biased out of engagement with the contact portion of the other member, said arm having a double-inclined cam upon the upper surface thereof, a relatively thin flat insulating plate positioned in a plane below the normal plane of said cam, said plate having an opening formed therein to accommodate said cam in one rotary

position of said plate, to permit disengagement of the free end of said resilient arm from the contact portion of the other member, said plate when rotated from said position cooperating with said cam to effect depression of said resilient arm, whereby the free end of the latter is engaged with the contact portion of the other member, means overlying said insulating plate to prevent substantial upward displacement of the latter, and manually operable means, including a shaft having a driving connection with said insulating plate, for effecting rotation of the latter in a given direction from and in the opposite direction to said one rotary position thereof to respectively make and break the circuit controlled by the switch.

14. In combination, a rotary actuating member for the resilient movable contacts of a switch of the slow-make, slow-break type, said member comprising a flat insulating plate of substantially circular contour, said plate having a central opening of angular contour formed therein, a rotary shaft of similar form in transverse cross section inserted into said opening and having driving en-

gagement with the walls of said opening, a plurality of pairs of contacts, one contact of each pair being biased by its own resiliency away from but forcibly movable into engagement with the other contact of said pair, each of said resilient movable contacts having a cam portion on the upper surface thereof, said plate being adapted to overlie said resilient movable contacts and being constrained to move in a given plane with respect to the latter, said plate having two arcuate openings formed therein concentric to and spaced different radial distances from said first mentioned opening and located in angularly spaced relation to each other, said last mentioned openings being adapted to accommodate the cam portions on said resilient movable contacts in one rotary position of said plate to permit disengagement of said movable contacts from the other contacts aforementioned, and said plate in all other rotary positions thereof acting against said cam portions to effect engagement of said movable contacts with the other contacts respectively. 5 10 15 20

GEORGE J. MEUER.
